UNITED STATES PATENT OFFICE.

CHRISTOPHER F. BACKMYER, OF CHICAGO, ILLINOIS, ASSIGNOR OF ONE-THIRD TO
EDWARD D. KIBBEN, OF CHICAGO, ILLINOIS.

GARMENT-FASTENER.

1,182,069.

Specification of Letters Patent.

Patented May 9, 1916.

Application filed February 26, 1915. Serial No. 10,715.

To all whom it may concern:

Be it known that I, CHRISTOPHER F. BACKMYER, a citizen of the United States, and a resident of the city of Chicago, in the county 5 of Cook and State of Illinois, have invented a certain new and useful Improvement in Garment-Fasteners; and I do hereby declare that the following description of my said invention, taken in connection with the 10 accompanying sheet of drawings, forms a full, clear, and exact specification, which will enable others skilled in the art to which it appertains to make and use the same.

My invention relates generally to improvements in garment fasteners, and it consists, essentially, in the novel and peculiar combination of parts and details of construction, as hereinafter first fully set forth and described and then pointed out in the 20 claims.

In the drawing already referred to, which it may be stated is enlarged to many times life size for clearness of disclosure, Figure 1 is a plan of the eye-member of my invention.

25 Fig. 2 is a cross section in line 4—4 of Fig. 1. Fig. 3 is a plan of the stud member of my invention. Fig. 4 is a cross section in line 6—6 of Fig. 3. Fig. 5 is a vertical section of the two members in assembled together condition.

Like parts are indicated by corresponding characters or symbols of reference in all the figures of the drawing.

The aim of this invention is the production of a fastener for the overlapping edges or seams of dresses, coats, waists and other garments in which the disadvantages of the typical hooks and eyes are eliminated. Among these disadvantages may be named 40 the liability of the hooks and eyes becoming disengaged from each other whereby the flap or seam of the garment becomes loosened and presents an unsightly appearance.

Another result aimed at in my invention 45 resides in the details of construction whereby the difficulty of hooking together the typical hooks and eyes is eliminated, and wherein a pull upon the fabric to enforce engagement of the parts is avoided. And yet 50 another advantage aimed at in this invention is to so construct the elements thereof that when the waist or other garment to which this fastener is attached is being ironed or passed through a wash wringer, 55 there will be no tendency to distort the fas-

tener itself and destroy its usefulness, as is now the case with the usual type of hooks and eyes.

To better understand my invention, I now refer to the drawing in which—

60 A is the eye member as a whole, which member is initially punched from a sheet or strip of sheet metallic material such as brass, steel, German silver and the like in the form of a flat disk A' with an integral, 65 outwardly projecting member B as seen in dotted lines in Fig. 1.

Pierced through the disk-like portion A' of the member A is a semi-circular opening 3 having a substantially U-shaped notch 3^a, 70 the whole forming a so called keyhole slot. The center of the opening 3 aforesaid is located away from the medial point of the disk-like portion A' toward the projection B, and it is now to be noted that a line 75 drawn medially of the width of the projection B will pass through the center of opening 3, through the center of the disk-like portion A' of the member A and medially of the width of the U-shaped notch 3^a for purposes 80 hereinafter described.

The disk-like part A' is stamped into a dome like curvature as at b and is provided with a marginal bead 5 for purposes of stiffness and also to provide a neat finish; 85 within the margin of this bead and concentric therewith are provided a plurality of oblong apertures 6, through which thread or similar media may be passed to fasten the member A to the fabric to which it is to be applied. Surrounding the opening 3 and its notch 3^a, is formed a depressed annular bead 7 to impart a certain degree of stiffness to the disk A', the material from which 90 said disk is made being only about 1-100 inch in thickness. The projection B is intended to be bent under the disk portion A'. The material from which the eye member A, constituting the disk A' and portion B is 95 of a spring nature as for instance spring brass and the like, and it is therefore evident that when the portion B is bent back under the disk A, the free end of said portion located under the keyhole slot in the disk will possess a certain degree of resiliency in a perpendicular direction.

100 The stud member, constituting the component part of this invention is indicated as a whole as E. It comprises a flat disk-like blank E', having a marginal bead 17^a and an 110

axial upstanding stud 20 possessed of an enlarged head 52 and a reduced neck 20^a, there being formed on the underside of said enlarged head an annular groove 53. Like the member A' the blank E is provided with a series of concentric apertures 25 for fastening purposes, and is likewise possessed of a concentric annular stiffening bead 18^a.

Attention is now directed to the fact that 10 the opening 3 in the disk A' of the eye-member A is provided with a downwardly inclined lip 50, to facilitate the entrance of the head 52 of the stud 20. The diameter of the opening 3 at the lower edge of said lip is 15 sufficiently large to permit the passage of said head, and it is of decidedly larger diameter at the plane of the face of the disk A', so that should the head 52 of the stud 20 be not in precise register with the opening 3, 20 the inclined lip 50 will quickly assist in placing the same in proper position. Depending from the end of the notch 3^a is a lip or flange 51 against which presses (when the eye-member A and stud member E are in un- 25 assembled condition) the upper face of the spring member B, as seen in Fig. 2. But, when the head 52 of the stud 20 is passed through the opening 3 and pressed against the spring member B, the free end of the latter is 30 caused to assume a resistingly declined position, and, when the said head has been forced downwardly to an elevation below the lower edge of the lip 51, then the spring member B has acquired a sufficient degree of declination 35 that the angularity of contact of the head of the stud with the resisting spring member will enforce a forward movement of the stud member, resulting in the entrance of the neck of the stud into the slot and the passage of 40 the head of said stud slightly beyond the periphery of the lip 51, at which time the upward pressure of the spring member B will cause upward movement of the stud member E and the embracement of the lip 51 by the groove 53, under the enlarged head 45 52 of the stud 20, whereby the stud and eye-member are locked together in a manner easily comprehended.

By reference to Fig. 5 it will be noted that 50 the peripheries of the eye and stud members, respectively, when assembled or locked together, are eccentrically disposed to each other. When it is desired to separate these members, the stud member is pressed downwardly to release the grooved head thereof from the lip 51, after which pressure by the thumb and index finger is applied to the opposite edge of the said members causing a backward movement of the stud member until the stud thereon is in register with the opening 3; whereon the pressure of the spring member B will eject said stud through the said opening.

Assuming now that the coacting members 60 A and E have been attached to component

flaps of a dress or other garment and that it is desired to hook up the garment. All that is necessary is to place the heads of the studs 20 of the successive stud members E in register with the openings 3 in the successive 70 eye member A and press slightly on the dress flap to propel in succession the heads of said studs through said openings, and, as said heads contact with and press against the spring member B the said parts become 75 locked together as already described. It will now be observed that in hooking up these fasteners, no pulling or pushing of the dress fabric is required, thus avoiding all danger 80 of tearing dainty fabrics, yet at the same time the same fasteners are just as efficient on heavier and coarser materials. It is intended that these fasteners will be plaited by the well known process of barrel plaiting so as to produce a neat finish in every respect. 85

Attention is directed to the fact that with the employment of the typical hooks and eyes, whenever a dress or waist is ironed, the nose of the smoothing iron invariably contacts with some of the hooks or eyes, which 90 are flattened or distorted out of shape, requiring a number of replacements. With the use of this invention all such annoyances are avoided.

It is to be understood that the disk-like 95 contour of the eye and the stud members, and the concentrically arranged openings therethrough, and the domed shape of the eye member all perform essential functions in my invention. Thus the circular contour 100 leaves no sharp angles or projections wherein a smoothing iron can catch while ironing a garment, the concentrically arranged thread openings permit a uniform fastening 105 of the fasteners to the garment at all points of the member and the dome shaped eye member is thoroughly protective of the spring member or portion B.

While I have herein disclosed the preferred method of practising my invention, I 110 reserve the right to make such changes and alterations as might occur to one skilled in the art or permitted under the doctrine of equivalents.

Having thus fully described my invention, 115 I claim as new and desire to secure to myself by Letters Patent of the United States:—

1. A garment fastener including a hollow, dome shaped member possessing an integrally formed spring leaf bent back under 120 said dome, said dome having an opening therethrough from which extends a slot, the end of which slot is provided with a downwardly projecting flange, the said spring leaf being adapted to be forced into a declining position under pressure, and a stud member having an enlarged head and a reduced neck, there being a groove on the under face of said head, said head being adapted 125 for entrance through said opening and 130 .

contact against said spring leaf, whereby upon the application of pressure upon said stud member, said leaf will be declined and the angularity of contact of said leaf with

5 said head will enforce forward movement of said stud member and the entrance of said reduced neck into said slot and likewise the embracement of said flange by said groove.

2. A garment fastener including an eye member having a slot possessed of a depending flange at one end and terminating in an enlarged opening, there being a depending lip partially surrounding said enlarged opening, an integrally formed spring leaf bent back from the margin of said eye member and extending beneath said openings, said leaf having a free end adapted for enforced downward movement, and a stud member having an enlarged head possessed 20 of a groove on its under side, and a reduced neck, adapted to project through said opening and to contact against said spring leaf, whereby the application of pressure to said stud member will create a declination of 25 said spring leaf and an angularity of contact of said head with said declined leaf, enforcing a forward movement of said mem-

ber and the entrance of said reduced neck into said slot, and likewise the embracement of said depending flange by said 30 groove.

3. A garment fastener including a substantially circular eye member formed integrally from a sheet metallic blank and having a spring tongue bent back under said blank, said blank being provided with a slot, one end of which slot is rounded and possessed of a downwardly extending flange surrounding said rounded portion, said slot terminating in an enlarged opening, and a 35 stud member including a circular base and an upstanding stud with an enlarged head, having an annular groove on the under side thereof, said tongue being adapted to press against said head and to enforce the projection of the lower edge of said flange into 40 said groove.

In testimony whereof I have hereunto set my hand in the presence of two subscribing witnesses.

CHRISTOPHER F. BACKMYER.

In the presence of—

W. HARDING,

WILLIAM O. STARK.
